FIGURE 1 is a front elevational view showing my new design of a gasoline dispenser unit, with a canopy.

FIGURE 2 is an end elevation of the unit of FIGURE 1 viewed from the left thereof.

FIGURE 3 is an end elevation of the unit of FIGURE 1 viewed from the right thereof.

FIGURE 4 is a front elevational view showing my new design of a gasoline dispenser unit, without a canopy.

FIGURE 5 is an end elevation of the unit of FIGURE 4 viewed from the left thereof.

FIGURE 6 is an end elevation of the unit of FIGURE 4 viewed from the right thereof.

FIGURE 7 is a front elevational view of my new design of a gasoline dispenser unit, showing a dual unit with a canopy.

FIGURE 8 is an end elevation of the unit of FIGURE 7 viewed from the right thereof.

FIGURE 9 is a front elevational view of my new design of a gasoline dispenser unit, showing a dual unit without a canopy.

FIGURE 10 is an end elevation of the unit of FIGURE 9 viewed from the right thereof.

The opposite sides of the units shown in FIGURES 1,

4, 7 and 9 and the opposite ends of the units shown in FIGURES 8 and 10 are substantially the same as the side and end shown in the respective figures.

The essential features of the design reside in the portions shown in full lines.

This application is a continuation application of my copending applications Serial Numbers D. 66,818; D. 66,819; D. 66,820 and D. 66,821 all of which were filed on September 22, 1961 and which have become abandoned since the filing of this application.

I claim:

The ornamental design for a gasoline dispenser unit, as shown and described.
